(57) **CLAIM**

The ornamental design for filter cartridge, as shown and described.

DESCRIPTION

FIG. 1 is a top perspective view of a filter cartridge according to the present design.

FIG. 2 is a first side elevational view of the filter cartridge of FIG. 1.

FIG. 3 is a second side elevational view, taken of a side opposite FIG. 2.

FIG. 4 is a third side elevational view, taken from the right toward the left with respect to the view of FIG. 2.

FIG. 5 is a fourth side elevational view opposite the view of FIG. 4.

FIG. 6 is a top plan view of the filter cartridge of FIG. 1; and, FIG. 7 is a bottom plan view of the filter cartridge of FIG. 1. The broken lines in the drawings form no part of the claimed design.
